UNITED STATES PATENT OFFICE.

WOJCIECH SZOSTEK, OF THREE RIVERS, MASSACHUSETTS.

COLLAPSIBLE CHAIR.

1,390,842.

Specification of Letters Patent. Patented Sept. 13, 1921.

Application filed June 18, 1921. Serial No. 478,514.

To all whom it may concern:

Be it known that I, WOJCIECH SZOSTEK, a citizen of Poland, residing at Three Rivers, in the county of Hampden and State of Massachusetts, have invented certain new and useful Improvements in Collapsible Chairs, of which the following is a specification.

The main object of this invention is the provision of a collapsible chair which may be quickly and compactly folded to occupy little space or to provide a convenient bundle so that the same may be readily carried about.

15 The above and other objects will become apparent in the description below, in which like-named characters of reference refer to like-named parts in the drawings.

Referring briefly to the drawings, Figure 20 1 is a side elevational view of my chair.

Fig. 2 is a front elevational view, partly in section on the line 2—2 of Fig. 1.

Fig. 3 is an underside plan view of the chair collapsed.

25 Fig. 4 is a similar view of the chair extended.

Referring now in detail to the drawings, the numeral 1 represents the seat of the chair having depending strips 2 at the rear edge and near the front edge. Spindles 3 are pivotally mounted on opposite sides of the chair in said strips, and legs 4 are rigid with said spindles at the four corners of the seat. The legs on one side of the chair

are spaced apart at a lesser distance than 35 those on the other, so that when the legs are folded under the seat, the legs on one side will not obstruct those on the other side.

The upper ends of the legs 4 are provided 40 with quadrantal sectors 5 engaging slideable racks 6 on the ends of slide bars 7. A hand lever 8 is pivotally mounted on the underside of the seat 1, at the rear, on a pin 9. Spaced apart slots 10 are provided in 45 said lever, and are engaged by pins 11 in the bars 7. The back of the chair 12 is hingedly attached at 13 to the seat. In operation, it is apparent that turning the lever 8 in one direction causes the legs to be 50 folded under the seat, and reverse turning causes the same to be extended.

I claim:

A collapsible chair comprising a seat, elements depending from opposite edges of 55 said seat, spindles pivotally mounted in said elements, legs rigidly secured to said spindles, toothed sectors on the upper ends of said legs, rack bars in engagement with said sectors and slidably mounted on the 60 underside of said seat, a lever pivotally mounted on the underside of said seat and having spaced apart slots therein, and pins on said bars lying in engagement with said slots. 65

In witness whereof I affix my signature.

WOJCIECH SZOSTEK.
